SETTLED PATENT

With Reference referred to in the Letter Patent and making part of the same containing a description in the body of the said Letter Patent himself of his improvement in the art of making Glue by evaporating the fat water or liquor from the boiling of bones of all kinds of animals

It is known that of Peter Coffey of New York in the County of New York & State of New York, have invented a new and useful improvement in the art of making Glue by evaporating the water commonly called the fat water or the liquor after the boiling the bones of all kinds of animals to a proper consistency for cutting, drying and making into glue by means of a double floored evaporating basin and that the following is a full and exact description of this construction and operation of the same as invented and improved by me. This improvement consists in having an oven or furnace made of brick work, from this furnace runs a horizontal chimney on the half the width and running the whole length in which it is intended to construct the evaporating basin, it is then returned on the other side back to the furnace where the glue terminates in a perpendicular chimney, across these two flues are to be laid at the top of the chimney two bars of about an inch and breadth to support the lower basin, upon these is laid an ironed sheet of Lead or other Metallic substance and upon the edges of this is placed a wooden curb, form little timber notches there, to the out side of this wooden curb the sheet lead is to be nailed all round & made to be made tight. Upon the bottom of the basin are laid three or four longitudinal strips of boards about 2 or 3 inches in width & terminating about a foot short of the inside of the curb at the end of each board from the furnace, logs of timber about an inch in diameter and about a foot or a half of about an inch thick are laid high & nailed to the longitudinal strips covered they will all the

board within the lower basin and will be covered with all the fuel and oil the
curb & curb and fuel form, it is a piece of board going around the basin
& forced to the inside of the wooden curb aforesaid. This board is to
be constructed about half an inch higher than the sea surrounding
and about two inches less in depth. - Upon these slats
is another sheet of lead extended, or other metallic substance
the edge of which is to be bent up and nailed to the inside of
the curb and the board aforesaid & so as to be suspending to the
water. This completes the construction of the evaporating basin
water is now to be poured in the open end of the lower basin, which
is beyond the board aforesaid until it fills up all the space that
is between the two basins. now is then put to the fire until the wa-
ter boils & then the hot water or liquor remaining after boiling the
oil from the bones of fish is to be run into the upper basin and the fire
light up until the hot water is evaporated to a proper consistence to
be taken out and put into cooling troughs where it afterwards is
left & spread on mats to dry. - This completes the process.

The improvement for which your Petitioner claims an
exclusive right is the construction of the double closed evaporating
basin & the application of it to the purposes of making Bleas
described as aforesaid, whereby the hot water or liquor after
boiling the bones of all kinds of fish may be evaporated into a
proper consistence to procure it and make it with Bleas.
